UNITED STATES PATENT OFFICE.

SIEGFRIED SCHANZER, OF NEW YORK, N. Y.

CAP.

Application filed August 4, 1921. Serial No. 489,677.

To all whom it may concern:

Be it known that I, SIEGFRIED SCHANZER, a citizen of the United States, residing in the borough of Manhattan, city, county, and State of New York, have invented an Improvement in Caps, of which the following is a specification.

This invention relates to a cap and more particularly to that form of knitted cap provided with an extension to cover the ears for children's wear, although it will be understood that the invention is not limited to a knitted cap or to the use of the same by children because it may be made in other manners and may be constructed as to be worn by adults. The invention furthermore consists in providing the cap with an extension having straps or other equivalent means adapted to be secured to the upper portions of the cap to normally maintain the extension in position and also when the extension is folded for use to be secured beneath the chin to maintain the cap and its extension in position on the head of the wearer. The cap made in accordance with my present invention will be hereinafter more particularly described in conjunction with the accompanying drawing, in which,

Fig. 1 is a perspective view showing the use of the cap.

Fig. 2 is a side elevation showing the parts of the cap folded to their normal positions.

Fig. 3 is a front elevation showing the parts of the cap in their extended positions.

Referring particularly to the drawing the cap made in accordance with my invention comprises a body portion 10 which may be constructed of knitted material or of material made in any other way. The body portion of the cap is preferably made to be yielding to snugly fit the head of the wearer and the back and side portions thereof are provided with a substantially wide flap or extension 11 made integral therewith or suitably connected thereto and adapted to normally fold over and lie against the outer portions of the body member at the lower part thereof. This flap extends across the back and sides of the body member and terminates at points at the front thereof. Adjacent its extremities the flap or extension 11 is provided with substantially narrow chin straps 12 and 13. These may be made of similar material and in a similar manner and may be integral with

the flap or suitably connected thereto. At the extremity of the strap 12 there is a loop 14 and at the extremity of the strap 13 there is a loop 15. When the flap or extension is in its normal position these straps are adapted to extend to the top central portion of the body member where there is a button 16 attached thereto to be engaged by the loops 14 and 15 to maintain the straps and the extension or flap in its normal folded up position. Of course it will be understood that a suitable snap or catch fastener or other means may be employed in lieu of the loops and button. When the extension or flap is turned down to cover the ears and the neck of the wearer the straps 12 and 13 may be passed beneath the chin and secured together by means of a button 17 attached to the strap 12 on the outer face thereof and a button hole or loop 15 to receive the same in the strap 13 or otherwise.

The cap as illustrated preferably includes a front flap or extension 19 which is normally secured in a folded up position by buttons 20 or otherwise and if desirable the construction may be such that this front flap or extension be turned down over the forehead or over the face of the wearer.

I claim as my invention:

A cap comprising a body member adapted to fit and cover the head of the wearer, a substantially wide integral extension depending from the back of said member forming neck and ear covering portions adapted to be turned up and down on a fold line between the extension and body member, integral chin straps narrower than said extension depending from and at right angles to each of said ear covering portions and having their ends each provided with a button-hole, one of said chin straps having its outer face provided with a button situated between and within the end portions and side margins thereof, and a button positioned at the apex of said body member and adapted to engage the buttonholes of said chin straps in overlapping relation at a single point when turned up, the button on said chin strap adapted to engage the buttonhole on the other chin strap when turned down holding the ends of the chin straps extending in different directions in lengthwise overlapping condition.

Signed by me this 27th day of July, 1921.
SIEGFRIED SCHANZER.
